UNITED STATES PATENT OFFICE.

ONESIME H. LE COMpte, OF OKLAHOMA CITY, OKLAHOMA.

LOCK-PIN LIFTING AND HOLDING DEVICE FOR AUTOMATIC CAR COUPLERS.

Application filed June 24, 1925. Serial No. 39,365.

My invention relates to a lock pin lifting and holding device for car couplers and it is a distinct and practical improvement to overcome certain practical objections to, and defects in, the present type of devices for a like purpose.

The object of my present invention is to provide means for lifting the lock pin for car couplers and to hold the lock pin in its elevated position until released by manipulating the operating lever rod.

Another object of the invention is the provision of a lock pin lifting and holding device for automatic car couplers, which will possess advantages in points of simplicity and efficiency, and, at the same time prove itself comparatively inexpensive in manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a view in perspective showing a device embodying the features of my invention as applied to the end of a car for lifting the lock pin of a car coupler.

Fig. 2, is a view partly in side elevation and partly in sectional elevation of my invention as applied to the end of a car.

Fig. 3, is a perspective view of the operating lever rod.

Fig. 4, is a perspective view of the pin lifting lever arm.

Fig. 5, is a perspective view of the supporting member to which the lock pin lifting lever arm is pivoted.

Referring to the drawing, the reference character 1 represents the end of a car provided with the usual head block 2, while 3 represents a suitable car coupler provided with a suitable lock pin 4.

In carrying out the aim of my present invention, I employ a suitable operating lever rod which consists of the body portion 5 which is provided at its outer end with a handle 6 which is bent downwardly at a right angle to the body portion. The inner end of the body portion 5 of the lever rod is bent rearwardly at a right angle to the body portion 5 and the handle 6 to provide an

actuating arm 7, as clearly shown in Figs. 1 and 3. The body portion 5 of the operating lever rod is mounted for operation in a pair of suitable bearings 8 which are suitably fixed to the end wall of the wall 1, as clearly shown in Fig. 1.

The reference character 9 represents a suitable supporting member consisting of a pair of spaced side walls 10 to provide a channel 11. The side walls 10 are preferably united by means of the bottom wall 12 although not necessarily so, and the side walls 10 are provided with base ears 13 having openings 14 for receiving suitable fastening devices 15 for securely fixing the supporting member to the upper face of the head block 2, as clearly shown in Figs. 1 and 5.

The reference numeral 16 represents a lock pin lifting lever arm, the rear end 17 of which is mounted in the guide channel 11 of the supporting member 9 and pivotally connected to the side walls 10 thereof by means of the pivot pin 18. The forward end of the lock pin lifting arm 16 is connected to the lock pin 4 by means of a suitable connection 19. The lower face of the rear end 17 of the lifting lever arm 16 is beveled, as at 20, so as to engage the upper face of the floor 12 of the channeled supporting member 9 when the forward end of the lifting lever arm is in its elevated position, as shown in full lines in Fig. 2, and out of engagement therewith when the forward end of the lifting lever arm is in its lowermost or normal position, as shown in dotted lines in Fig. 2.

The upper face of the rear end portion 17 of the lever arm 16 is provided with a stop shoulder 21 for engagement with the free end of the actuating arm 7 of the operating lever rod 5 when the rear end portion 17 of the lifting lever arm has been depressed by manipulating the lever rod 5 for raising the forward end of the lifting lever arm 16, which movement raises or lifts the lock pin 4 of the car coupler 3, as clearly shown in Fig. 2. The lock pin 4 is held in its elevated position by means of the actuating arm 7 of the operating lever rod 5 when assuming a perpendicular position and prevents the fall or drop of the lock pin until the handle section 6 of the operating lever arm 5 has been moved downwardly to its normal position which causes the actuating arm 7 to move into its normal or horizontal position for releasing the rear end of the lock pin

lifting lever arm and permit the forward end thereof to move downwardly thereby permitting the lock pin 4 to fall into its closed position by means of gravity.

5. The many advantages of the herein described invention will readily suggest themselves to those skilled in the art to which it appertains.

I do not desire to be understood as having limited myself to the exact details of construction and arrangement of parts as herein described and illustrated, as it is manifest that variations and modifications may be made without departing from the spirit and scope of my invention, and the terms of the following claims, hence I wish it to be understood that I reserve the right to make any such changes, or modifications as may fairly fall within the scope of the appended claims when fairly construed.

What I claim is:

1. In a means for operating automatic car couplers, the combination with a gravity lock pin, of an operating lever rod, a pivotally supported lock pin lifting lever arm, a connection between the lifting lever arm and the lock pin and means carried by the operating lever rod adapted for engagement with the upper flat face of the rear end of the lifting lever arm for elevating the lock pin and holding the pin in its elevated position.

2. In a means for operating automatic car couplers, the combination with a gravity lock pin, of an operating lever rod, a pivotally supported lock pin lifting lever arm, a connection between the lifting lever arm and the lock pin, an actuating arm directed rearwardly from the inner end of the operating lever rod for engagement with the rear end of the lifting lever arm when lowered in an arcuate path to lower the rear end of the lifting lever arm and raise the forward end thereof to elevate the lock pin and a shoulder at the rear end of the lifting lever arm to engage the actuating arm when in its operative position.

3. In a means for operating automatic car couplers, the combination with a gravity lock pin, of an operating lever rod, a channeled member, a lever arm pivotally connected to said member with its rear portion seated within the channel thereof, a connection between the forward end of the lever arm and the lock pin, and means actuated by the lever arm for lowering the rear end of the lever arm and raising the forward end thereof for elevating the lock pin and holding the pin in its elevated position.

4. The combination of the locking pin of an automatic coupler, a channeled saddle member, a lever arm pivotally supported between the side walls of the channeled saddle member, a connection between one end of the lever arm and the locking pin, an operating lever rod and an arm directed

from the inner end of the lever rod for engaging the upper face of the inner end of the lever arm to lower said inner end of the lever arm and elevate the locking pin upon oscillating manipulation of the operating lever rod in one direction.

5. The combination of the locking pin of an automatic coupler, a longitudinally directed pivotally supported lever arm, a connection between one end of the lever arm and the locking pin, an operating lever rod, an arm directed from the inner end of said rod at a right angle thereto and engaging the upper face of the inner end of the lever arm for forcing the inner end of the lever arm downwardly thereby elevating the locking pin and holding the same in its elevated position.

6. In combination with the locking pin of an automatic coupler, a lever arm having an angularly shaped lower face and provided with a cutaway portion at its inner upper corner to provide a flat upper face and a shoulder at the outer end thereof, means for pivotally supporting said lever arm and preventing lateral displacement thereof and oscillating means for engagement with said flat upper face to lower the rear end portion of the lever arm for elevating the locking pin and holding the locking pin in its elevated position.

7. In combination with the locking pin of an automatic car coupler, a U-shaped saddle member fixed to the end of a car, a lever arm pivotally connected to said U-shaped member near its inner end, the rear end portion of said lever arm being disposed between the walls of the U-shaped member and the forward end portion thereof extending beyond the outer ends thereof, a connection between the extended end of said lever arm and the locking pin and rocker member for actuating said lever arm to elevate the locking pin and holding the pin in such elevated position until released.

8. In a car coupler, the combination with the locking pin thereof, of a channeled saddle member having its longitudinal axis directed longitudinally of the car body, a lifting lever arm pivoted near its inner end between the walls of the saddle member with a portion of its lower face in contact with the floor of the saddle member in its pin lifting position, a connection between the outer end of the lever arm and the locking pin, said lever arm having a flat upper surface at its inner end, a shoulder formed at the inner end of the flat upper surface, a horizontally disposed operating lever rod having a handle at its outer end and a stub arm directed from the inner end of said operating lever rod at a right-angle thereto, the free end of which lever rod is adapted to engage the flat upper face of the lever arm for elevating the outer end of the lever arm and locking

pin simultaneously and to hold the outer end of the lever arm in its raised position when the stub arm has assumed a vertical position and is in contact on one side there-
5 of with the shoulder of the lever arm.

9. In a means for operating automatic car couplers, the combination with a gravity lock pin, of an operating lever rod, a piv-
10 otally supported lock pin lifting lever arm,
10 a connection between the lifting lever arm and the lock pin, an actuating arm directed rearwardly from the inner end of the operating lever rod for engagement with the upper face of the rear end of the lifting lever
15 arm when lowered in an arcuate path to lower the rear end of the lifting lever arm and raise the forward end thereof to elevate the lock pin and a shoulder at the for-
ward end of said upper flat face of the lift-

ing lever arm to engage the actuating arm 20 when in its operative position.

10. In a means for operating automatic car couplers, the combination with a gravity lock pin, of an operating lever rod, a channeled saddle member, a lever arm piv-
25 otally connected to the side walls of said channeled saddle member with its rear portion disposed within the channel thereof, a connection between the forward end of the lever arm and the lock pin, and an arm di-
30 rected from the inner end of the lever arm for engagement with the upper surface of the rear end of the lever arm for lowering the rear end of the lever arm and raising the forward end thereof for elevating the lock 35 pin and holding the pin in its elevated position.

ONESIME H. LE COMpte.
